UNITED STATES PATENT OFFICE.

WILLIAM JOSEPH IRWIN, OF NEW YORK, N. Y.

DESIGN FOR A FISH-CLEANING KNIFE.

SPECIFICATION forming part of Design No. 32,329, dated March 13, 1900.

Application filed February 12, 1900. Serial No. 5,023. Term of patent 7 years.

To all whom it may concern.

Be it known that I, WILLIAM JOSEPH IRWIN, a citizen of the United States, and a resident of the city of New York, borough of Manhattan, in the county and State of New York, have invented and produced a new and original Design for a Fish-Cleaning Knife, of which the following is a full, clear, and exact description.

Reference is to be had to the accompanying drawings, forming a part of this specification, in which similar characters of reference indicate corresponding parts in both the views.

Figure 1 is a perspective view of a fish-cleaning knife, showing my design; and Fig. 2 is a front end view of the same.

The design in its entirety consists of a shank A, appearing at the rear end with a handle B and at the front end with a head C, having downwardly and outwardly extending side flanges, below which appear the parallel knife-blades D D', formed with upwardly-extending

lugs D², appearing raised on the sides of the shank A, the bottom edges of said blades appearing in a horizontal plane approximately 25 parallel with the under side of the head and shank and the top edges of said blades extending from a forward point upwardly and rearwardly to the front edges of the lugs D².

The leading features of the design consist 30 of the flanged heads and the depending knife-blades.

Having thus fully described my invention, I claim as new and desire to secure by Letters Patent—

The design for a fish-cleaning knife, as herein shown and described.

In testimony whereof I have signed my name to this specification in the presence of two subscribing witnesses.

WILLIAM JOSEPH IRWIN.
